(57) **CLAIM**

The ornamental design for a knob for electronic oven, as shown and described.

DESCRIPTION

FIG. 1 is a top front perspective view of a knob for electronic oven showing our new design;

FIG. 2 is a front elevational view thereof;

FIG. 3 is a rear elevational view thereof;

FIG. 4 is a left side elevational view, the right side being symmetrical thereof; and,

FIG. 5 is a top plan view, the bottom plan being symmetrical thereof.
